CONTROLLING MECHANISM FOR REFRIGERATING APPARATUS

Filed Feb. 7, 1927

UNITED STATES PATENT OFFICE

JOHN R. REPLOGLE, OF DETROIT, MICHIGAN, ASSIGNOR TO KELVINATOR CORPORATION, OF DETROIT, MICHIGAN, A CORPORATION OF MICHIGAN

CONTROLLING MECHANISM FOR REFRIGERATING APPARATUS

Application filed February 7, 1927. Serial No. 166,277.

This invention relates to automatic control mechanism for artificial refrigerating systems.

An object of my invention is to maintain a predetermined range of low temperature in a chamber to be cooled with an artificial refrigerating system in which the power appliance is automatically controlled by mechanism responsive to the temperature of the refrigerant in the low side.

Another object of my invention is to provide a fluid pressure device which is responsive to the temperature of the refrigerant in the low side of an artificial refrigerating system to affect mechanism associated to control the operation of the power appliance.

These and other objects will be more apparent as the description progresses, in which like characters designate like parts in the accompanying drawing illustrating a preferred embodiment of the invention.

In the drawing:

Fig. 1 is a fragmentary sectional view of a cooling unit including a brine tank and evaporator showing my invention associated therewith.

Fig. 2 is a front elevational view of the same showing the control and refrigerant conduits associated therewith, and

Fig. 3 is a diagrammatic view of an artificial refrigerating system incorporating the invention.

My invention is associated with a refrigerating system of conventional construction which comprises a cooling unit B, a compressor-condenser unit A, and a power appliance or motor M.

The cooling unit of the refrigerating system includes a brine tank 10 and an evaporator 11 supported interiorly thereof, the said evaporator structure including a header 12 and depending pipe loops 13 secured to the header and in open communication therewith, one end of the evaporator header being closed by the end plate 14. One wall of the brine tank is provided with a large opening 15, the closure plate 16 being secured to the brine tank by the bolts 17 to close the opening. The end plate 14 of the evaporator is secured to the closure plate, the entire evaporator

structure being removed and inserted as a unitary structure through the large opening 15 in the wall of the brine tank. The end plate of the evaporator header is provided with refrigerant inlet and outlet passages 18 and 19 respectively, suitable float controlled valve mechanism 20 being associated with the inlet passage to automatically maintain a substantial constant quantity of liquid refrigerant within the evaporator and suitable valved couplings 21 are connected with these inlet and outlet passages. A refrigerant feed conduit 22 connects the coupling adjacent said inlet passage 18 with a reservoir for the condensed refrigerant interiorly of the casing 23 surmounting the compressor-condenser unit A and the refrigerant return conduit 22—a connects the crankcase 24 of the compressor with the coupling adjacent the outlet passage 19, thus completing a closed circuit between the evaporator and compressor, and the evaporator and refrigerant reservoir.

The mechanism for controlling the operation of the system comprises a pressure controlled switch actuating mechanism 33 and thermal responsive means D connected therewith which is associated with the low side of the refrigerating system. The thermal responsive means includes a receptacle 25, preferably a long copper tube, which is secured to the inner face of the end plate and extends interiorly of the evaporator. This tube is closed at its inner end by the plug 26 and is adapted to contain a heat responsive fluid that will expand when subjected to a rise in temperature. The interior of said tube is in open communication with the passage 27 through the end plate 14, and a fitting 29 is secured to the exterior face of the end plate, said fitting being provided with a passage 30 in open communication with the passage 27 and the interior of the tube. A conduit 32 connects the passage 30 with the pressure controlled switch actuating mechanism 33. The particular form of switch mechanism forms no part of the present invention, and is fully described in my co-pending application Serial No. 475,344, filed June 6, 1921, 100

which has matured into Patent No. 1,823,002, dated September 15, 1931.

- A rise in temperature within the evaporator will affect the fluid within the receptacle or tube 25, thereby increasing the pressure of the fluid, the effect of this increased pressure being transmitted through the communicating passages 27 and 30, and the conduit 32 to the switch actuating mechanism 33. 5
- 10 The switch actuating mechanism is adjusted to snap the switch 34 "on" when the pressure of the fluid reaches a predetermined maximum, thus completing the electrical circuit through the motor M for operating the compressor. This pressure controlled switch actuating mechanism may be adjusted to regulate the operation of the power appliance and compressor to maintain the temperature of the evaporator within a predetermined range. 15
- 20

As stated above, the fluid in the tube should be responsive to temperature changes and should expand when subjected to increased temperatures. Various fluids may be used in 25 the tube, but I prefer to use the same heat responsive fluid within the tube which is used as the refrigerant in the refrigerating system, for the reason that similar pressure conditions may be had within the tube as in the 30 evaporator, thereby giving more accurate results and permitting the accurate maintenance of temperatures in the evaporator within a predetermined range.

I find it convenient to charge the tube with 35 refrigerant taken from the evaporator. To accomplish this, the tube is inclined downwardly, the inner end of the tube being submerged in the refrigerant. The plug that closes the inner end of the tube is provided 40 with a passage 40, and adjustably supports the valve 41 for closing the passage 40. The valve is carried by the valve stem 42 which extends interiorly of the tube and through the packing 43 into a chamber interiorly of 45 the fitting 29. Access may be had to the valve stem by removing the plug 44, the end of the valve stem being shaped to permit the application of a wrench. Thus the passage 40 may be opened to permit refrigerant to 50 flow into the tube by manually turning the valve stem, thereby unseating the valve carried by said valve stem. The valve is closed when the proper amount of refrigerant has 55 been admitted to the tube. With such a construction it is possible to recharge the tube with expansible fluid whenever necessary.

It will be noted that the mechanism described above permits the maintenance of predetermined range of low temperature in a 60 chamber to be cooled. Temperature changes within said chamber affect the temperature of the refrigerant within the evaporator, causing vaporization of the liquid refrigerant and an increase in pressure therein. The temperature of the fluid in the tube extending

interiorly of the evaporator is correspondingly affected, the rise in temperature causing the fluid to vaporize, thereby causing a corresponding increase in pressure. When the pressure of the fluid reaches a predetermined maximum the power appliance is started in operation, the compressor operated thereby withdrawing vaporized refrigerant from the evaporator thereby reducing the pressure and temperature of the refrigerant in the evaporator, the temperature and pressure of the fluid in the tube being likewise affected. When the pressure of the fluid in the tube reaches a predetermined minimum, the power appliance is stopped. 70

75 The tube 25 is preferably submerged in the refrigerant to obtain a more direct thermal contact between the refrigerant in the evaporator and the fluid in the tube. The separate enclosed control means is solely responsive to temperature changes within the chamber to be cooled, and because of its location and the character of the fluid contained therein, a very accurate and sensitive control may be had of the operation of the refrigerating apparatus. 80

85 Various changes can be made in the type of heat responsive structure shown, and other details of the control mechanism, without departing from the spirit of my invention and 90 the scope of what is claimed.

I claim:

1. The combination with an artificial refrigerating apparatus supplied with power including a refrigerant evaporator of a temperature responsive device for controlling the operation of the apparatus, comprising: an elongated tube disposed within the evaporator and having one end secured to a wall thereof and connected to the power supply for the apparatus, means at the opposite end of the tube for admitting refrigerant from the evaporator to the tube and means for controlling said latter means. 100

105 2. The combination with an artificial refrigerating apparatus supplied with power including a refrigerant evaporator of a temperature responsive device for controlling the operation of the apparatus, comprising: an elongated tube disposed within the evaporator and having one end secured to a wall of the evaporator and connected to the power supply for the apparatus, a valve at the opposite end of the tube whereby refrigerant may be admitted thereto, and means projecting from the first mentioned end of the tube for operating the valve. 110

115 3. The combination with an artificial refrigerating apparatus supplied with power including a refrigerant evaporator of a temperature responsive device for controlling the operation of the apparatus, comprising: an elongated tube disposed within the evaporator and having one end communicating with a passageway in the head and connected to 120 125 130

the power supply for the apparatus, a valve at the opposite end of the tube whereby refrigerant may be admitted thereto, means extending into the passageway for controlling the operation of the valve, and a cap for closing the first mentioned end of the passageway.

4. The combination with an artificial refrigerating apparatus supplied with power including a refrigerant evaporator of a temperature responsive device for controlling the operation of the apparatus, comprising: an elongated tube disposed within the evaporator and having one end secured to a wall of the evaporator and connected to the power supply for the apparatus, a valve at the opposite end of the tube whereby refrigerant may be admitted thereto, and means operable exteriorly of the evaporator for opening and closing the valve.

In testimony whereof I hereunto affix my signature.

JOHN R. REPLOGLE.
